Primary Examiner — Mark A Goodwin*Assistant Examiner* — Benjamin M Weeks(74) *Attorney, Agent, or Firm* — Nixon & Vanderhye(57) **CLAIM**

I claim the ornamental design for a baseplate, as shown and described.

DESCRIPTION

FIG. 1 is a top plan view of a baseplate showing the new design;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a bottom plan view thereof; and,

FIG. 7 is a top, right side, and front perspective view thereof. The broken lines shown in the drawings illustrate portions of the baseplate that form no part of the claimed design.
